UNITED STATES PATENT OFFICE.

GRANT C. MACOMBER, OF BATTLE CREEK, MICHIGAN.

REVERSIBLE SHAFT-GOVERNOR.

No. 832,990.

Specification of Letters Patent.

Patented Oct. 9, 1906.

Application filed February 8, 1906. Serial No. 300,176.

To all whom it may concern:

Be it known that I, GRANT C. MACOMBER, a citizen of the United States, residing at Battle Creek, in the county of Calhoun and 5 State of Michigan, have invented new and useful Improvements in Reversible Shaft-Governors, of which the following is a specification.

This invention relates to a reversible shaft-governor.

A device involving my invention may be used advantageously in many different ways, one of which is in conjunction with the valve of a steam-engine.

The primary object of the invention is to provide a simple device of the character set forth which is effective in operation and which can be instantly and easily reversed by an engineer.

The device is compact, its parts are thoroughly protected, and it may be applied to the crank-shaft of an engine of any suitable type.

In order to enable those skilled in the art to practice the invention, I have illustrated in detail in the drawings accompanying and forming a part of this specification one form of embodiment of the invention, which I will fully set forth in the following description.

The novelty of the invention will be included in the claims succeeding said description.

In the drawings, Figure 1 is a central longitudinal section of a governor including my invention. Fig. 2 is a transverse sectional elevation of the governor, the section being on the line 2 2 of Fig. 1. Fig. 3 is a transverse section of the governor on the line 3 3 of Fig. 1. Fig. 4 is a similar section on the line 4 4 of Fig. 1.

Like reference characters refer to like parts throughout the several views.

The different parts of the governor may be supported by any suitable carrier. I have shown a carrier for this purpose and have denoted the same in a general way by 2. The carrier consists of a substantially wheel-like casing. The carrier or casing 2 is ordinarily rotative with the crank-shaft of the engine with which the governor is associated, and 50 for this purpose it may be keyed or pinned to said shaft. So that the carrier or casing may have an ample bearing upon the shaft the former is provided with oppositely-disposed hubs 3 and 4, an eccentric, as 5, surrounding 55 the hub 4. The eccentric 5 is contiguous to one of the outer faces of the carrier or casing

2, and it has a flange, as 6, extending into the interior of the casing through a slot in one of the walls thereof, said flange being provided with an enlargement or hub, as 7, into the opposite ends of which are tapped pivot-screws, as 8, constituting pivots or journals for the eccentric, the heads of the screws being mounted for rocking motion in journal-openings in the opposite walls of the casing 2. 65 From this it will be understood that the eccentric may be adjusted. By separating the screws 8 from the eccentric the latter can be disconnected from its carrier, it being understood that for this purpose the hub 4 is not 70 integral with the body of the casing 2. The bearings upon which the eccentric 5 oscillates are protected from the action of dust and other flying particles. The eccentric 5 has an inwardly-disposed toothed segment, as 9, 75 situated in a segmental slot formed in the outer face of one of the walls of the casing 2. Screws, as 10, tapped into the end walls of said slots serve as convenient adjustable stops for limiting the motion of the segment 9 80 and necessarily of the eccentric, of which said segment in the present case forms an integral part.

Supported by suitable bearings removably associated with the casing 2 is a rock-shaft, 85 as 11, which is provided at one end with a gear, as 12, meshing with the teeth of the segment 9, the action being such that when the shaft 11 is turned the eccentric 5, through the intermediate meshing toothed parts, will be 90 angularly adjusted to vary its stroke, assuming that it originally occupied a dead-center position. The gear 12 is fastened to its shaft in any desirable way and rotates in an opening in one of the outer faces of the casing 2, 95 which opening intersects the slot in which the segment 9 is located. The two toothed parts are in this way protected, they being partially housed by the casing 2.

A bar is represented as 13 and as attached 100 in any desirable way substantially centrally of its length to the rock-shaft 11 in order to present two oppositely-disposed arms or branches of equal length. The branches or arms of the bar 13 are jointed at their outer 105 ends to links, as 14, jointed in turn at their outer ends to oscillatory weights, as 15, pivotally supported between the opposite walls of the casing 2. The pivots for the two oscillatory or swinging weights are removably 110 mounted, so that when occasion requires the weights can be dismounted. Between the

weights and acting against the same I have shown a pull-spring, as 16, of coil form, one end of the spring being provided with a threaded stem 17, tapped into one of the 5 weights; while the opposite end of said spring is provided with a loop or eye connected with the other weight. The normal tendency of the spring is to draw the weights inward or toward each other. When the eccentric is in 10 its neutral position, the pivots between the bar 13 and links 14 and links 14 and weights 15 will be in line with each other, the bar and links acting as a locking-toggle to maintain the weights separated their maximum extent. When, however, the pivots are thrown 15 out of line or the locking-toggle alluded to is broken, the spring 16 becomes effective for drawing the weights inward, so that under the action of the rotating shaft with which 20 the governor is associated the weights may be thrown out by centrifugal action when the speed of the engine exceeds a certain standard.

Surrounding the eccentric 5 is a divided ring 18, connected by a rod, as 19, with the 25 slide-valve of the engine, such slide-valve not being shown. By throwing the eccentric in either direction the eccentric when shifted serves to operate the said valve, and as the eccentric is adjustable the stroke of the said 30 valve may be regulated. By moving the eccentric to the opposite side of said neutral position the engine may be reversed, and these different movements of the eccentric are in the present case adapted to be controlled by 35 the engineer, and I will now set forth the means shown for this purpose.

Rotative with the engine-shaft and necessarily with the casing 2 is a sleeve 20, which is moved longitudinally of said shaft by one 40 arm of a lever, as 21, the lever being shown as being of angle form and being fulcrumed in any desirable way at its elbow. The other arm of the lever may be operated by hand in any desirable way to move the sleeve 20 longitudinally of the shaft. The sleeve 20 is provided with an auxiliary sleeve, as 22, which freely receives the screw or spiral 23, constituting a rigid extension of the rock- 45 shaft 11, and between the threads of the screw are freely fitted opposite projections 24, rigid with the sleeve 22 and diagonally disposed therein. The primary function of the screw 23 and co-operating projections 24 is when the sleeve 20 is moved longitudinally of the shaft to break the toggle consisting of the 50 bar 13 and links 14, so that the spring 16 can draw the weights 15 inward. When the eccentric 5 is in its neutral position, what may be considered the "forward ends" of the projections 24 are against the threaded part of the screw 23, the tails or butts of said projections being out of contact with said threaded part. It therefore follows that when the 55 sleeve 20 is moved toward the casing 2 the projections 24 will turn the screw 23, and

therefore the rock-shaft 11, in order to break the toggle consisting of the bar 13 and links 14. As soon as this toggle is broken the two weights 15 can be swung inward by their 70 spring 16, and as they swing inward the rock-shaft 11, through the intermediate parts, is turned to throw the eccentric through the medium of the intermeshing gear 12 and segment 9. The eccentric may be set to any angle, and as the shaft rotates and when the 75 speed thereof exceeds a certain point the co-operating weights are thrown outward in order, through the intermediate parts, to move the eccentric toward its neutral position, this being permitted by reason of the fact that the 80 projections 24 have a free fit in the groove of the screw 23. By running the sleeve all the way in and maintaining it in such relation to the rocking motion of the shaft 11, and therefore outward motion of the weights 15, will be prevented in case it is desired for any cause to throw the governor out of action. By operating the sleeve 20 the motion of the engine 85 may be, as will be clearly evident, reversed at any time.

The threaded stem 17 is provided with a nut 25, carrying a gear, as 26, shown as being of bevel form, and meshing with a co-operating bevel-gear 27, carried by a shaft 28, the outer end or head of the shaft being provided 90 with lugs 29 to co-operate with one of the branches of a fork, as 30, carried by a rod 31, supported for turning motion upon suitable brackets or bearings on the framework of the engine. The branches of the fork 30 are normally out of contact with the lugs 29. When, however, it is desired to regulate the tension of the spring 16, the rod 31 will be so turned that one of the branches thereof will be in the path of the lugs 29 as the governor rotates, so 95 that on such rotation said branch may engage the lugs to turn the shaft 28, and thereby, through the intermediate gears 27 and 26 and nut 25, adjust the tension of the spring. In this way I provide for the regulation of 100 the tension of the spring while the governor is in motion.

What I claim is—

1. In a governor, a rotary carrier, weights supported for oscillation by the carrier, spring means for moving the weights toward each other, an eccentric supported by the carrier and provided with a segment, a shaft provided with a gear meshing with said segment, a bar fixed to the shaft, links connected with the bar and with the weights, the bar and links constituting a toggle to lock the weights against movement toward each other, and means for breaking the toggle to permit the weights to be moved toward each other by said spring means.

2. In a governor, a rotary carrier, weights supported for oscillation by the carrier, spring means for moving the weights toward each other, an eccentric supported by the car- 130

rier and provided with a segment, a shaft provided with a gear meshing with said segment, a bar fixed to the shaft, links connected with the bar and with the weights, the 5 bar and links constituting a toggle to lock the weights against movement toward each other, and manually-operable means for turning said shaft.

3. In a governor, a rotary carrier, weights 10 supported for oscillation by the carrier, spring means for moving the weights toward each other, an eccentric supported by the carrier and provided with a segment, a shaft provided with a gear meshing with said segment and also provided with a screw, a bar carried by the shaft, links connected with the bar and with the weights, the bar and links constituting a toggle to lock the weights 15 against movement toward each other, and a movable member having projections fitted freely in the groove of the screw, said member when moved serving to turn the shaft and thereby break said toggle to permit the weights to be moved toward each other by 20 said spring.

4. In a governor, a rotary carrier, weights supported for oscillation by the carrier, spring means for moving the weights toward each other, an eccentric supported by the carrier and provided with a segment, a shaft provided with a gear meshing with said segment and also provided with a screw, a bar carried by the shaft, links connected with the bar and with the weights, the bar and links 35 constituting a toggle to lock the weights against movement toward each other, a movable member having projections fitted freely in the groove of the screw, said member when moved serving to turn the shaft and thereby 40 break said toggle to permit the weights to be moved toward each other by said spring, and means for tensioning the spring means during the rotation of said carrier.

5. In a governor, a rotary carrier, weights 45 supported for oscillation by the carrier, spring means for moving the weights toward each other, an eccentric supported by the carrier and provided with a segment, a shaft provided with a gear meshing with said segment and also provided with a screw, a bar 50 fixed to the shaft, links connected with the bar and with the weights, the bar and links

constituting a toggle to lock the weights against movement toward each other, an endwise-movable sleeve provided with an auxiliary sleeve having opposite projections 55 therein to freely fit in the groove of said screw, and manually-operable means for moving said first-mentioned sleeve in an endwise direction. 60

6. In a governor, a rotary carrier, weights supported for oscillation by the carrier, spring means for moving the weights toward each other, an eccentric supported by the carrier and provided with a segment, a shaft 65 provided with a gear meshing with said segment and also provided with a screw, a bar fixed to the shaft, links connected with the bar and with the weights, the bar and links constituting a toggle to lock the weights 70 against movement toward each other, an endwise-movable sleeve provided with an auxiliary sleeve having opposite projections therein to freely fit in the groove of said screw, and a lever acting against the last- 75 mentioned sleeve to move the same in an endwise direction.

7. In a governor, a rotary carrier, weights supported for oscillation by the carrier, a spring connecting the weights and provided with a threaded stem tapped into one of said weights, a nut on the stem, and mechanism for turning the nut during the rotation of the carrier, to thereby effect the regulation of the tension of said spring. 80

8. In a governor, a rotary carrier, weights supported for oscillation by the carrier, a spring connecting the weights provided with a threaded stem tapped in one of the weights, a nut on the threaded stem, a gear carried by 90 the nut, a second gear meshing with the first-mentioned gear and provided with a head having lugs, and a member provided with projections, each adapted to engage the lugs to effect the regulation of the tension of 95 the spring.

In testimony whereof I have hereunto set my hand in presence of two subscribing witnesses.

GRANT C. MACOMBER.
